BUCKLE FRAME

Paul W. White, New Haven, Conn., assignor to
Parva Products Company, Chicago, Ill., a cor-
poration of Delaware

Application October 31, 1950, Serial No. 12,791

Term of patent 14 years

(Cl. D17—1)

To all whom it may concern:

Be it known that I, Paul W. White, a citizen of the United States, residing at New Haven, in the county of New Haven and State of Connecticut, have invented a new, original, and ornamental Design for a Buckle Frame, of which the following is a specification, reference being had to the accompanying drawing, forming a part thereof, in which:

Fig. 1 is a perspective view of a buckle frame embodying my new design;

Fig. 2 is a side elevational view of the buckle frame shown in Fig. 1;

Fig. 3 is a plan view of the buckle frame shown in Fig. 1; and

Fig. 4 is an end view thereof taken from the lefthand end of Fig. 3.

The characterizing features of my new design are shown in full lines in the drawing.

I claim:

The ornamental design for a buckle frame, substantially as shown and described.

PAUL W. WHITE.
